[57] CLAIM

The ornamental design for a jewelry setting, as shown and described.

DESCRIPTION

FIG. 1 is a front elevation view of a jewelry setting illustrating my new design, the back view being identical in appearance;

FIG. 2 is a right side view thereof, the left view being identical in appearance;

FIG. 3 is a top elevation view thereof, the bottom view being identical in appearance;

FIG. 4 is a front elevation view of a second embodiment of my new design, the back view being identical in appearance;

FIG. 5 is a right side view thereof, the left view being identical in appearance; and,

FIG. 6 is a top elevation view thereof, the bottom view being identical in appearance.

FIG. 1.

FIG. 2.

FIG. 3.

FIG. 4.

FIG. 5.

FIG. 6.
